UNITED STATES PATENT OFFICE.

SAMUEL HIRSCH, OF NEW YORK, N. Y.

BOY'S BLOUSE.

SPECIFICATION forming part of Letters Patent No. 776,324, dated November 29, 1904.

Application filed September 1, 1904. Serial No. 222,922. (No model.)

To all whom it may concern:

Be it known that I, SAMUEL HIRSCH, a citizen of the United States, residing at New York, in the county of New York and State of New York, have invented certain new and useful Improvements in Boys' Blouses, of which the following is a specification, such as will enable those skilled in the art to which it appertains to make and use the same.

10 This invention relates to boys' blouses; and the object thereof is to provide a garment of this class of improved construction and provided with improved means for connecting the blouse with the waistband of the trousers; 15 and with this and other objects in view the invention consists in a garment of the class specified constructed as hereinafter described and claimed.

The invention is fully disclosed in the following specification, of which the accompanying drawings form a part, in which the separate parts of my improvement are designated by suitable reference characters in each of the views, and in which—

20 Figure 1 is a perspective view showing my improved blouse and also showing a pair of trousers and the method of wearing the blouse; Fig. 2, a partial section on the line 2 2 of Fig. 1, and Fig. 3 a partial section on the line 3 3 25 of Fig. 1.

Figure 1 shows my improved blouse *a*, which is longer from the neck to the bottom of the blouse than the distance between the neck of the wearer and the waistband of the trousers, a pair of trousers being shown at *b*.

Passing over each shoulder of the blouse and extending downwardly to a point at a predetermined distance above the bottom of the blouse, both at the front and back thereof, is a box-plait *c*, and these box-plaits are stitched to the material of the blouse, as shown at *d*. The box-plaits *c* are on the outer side of the blouse as shown, and the material of the blouse at the front and back and at a predetermined distance above the bottom thereof is cut to form openings *e*, through which are passed straps *f*, which also pass over the shoulders and through pockets *g*, formed by the box-plaits *c*. The openings in the body of the

blouse through which the straps *f* are passed are at a predetermined distance above the waistband of the trousers when the blouse is on the wearer, and the ends of the straps *f* at the back are provided with buttons *h*, which 55 are adapted to be connected with the waistband of the trousers, and a number of these buttons are provided whereby the lengths of the straps *f* at the back may be adjusted, or said straps *f* may be provided at the back 60 with buttonholes and the trouser-waistband *b* may be provided with buttons.

The front ends of the straps *f* are formed into loops *f*², through which are passed supplemental suspending-straps *i*, which are 65 adapted to be connected with the waistband of the trousers at the front, and for this purpose the supplemental suspending-straps *i* are provided with buttons *i*², or the waistband *b*² of the trousers may be provided with buttons 70 and the supplemental suspending-straps *i* with buttonholes. That part of the straps *f* at the front which is bent upwardly to form the loops *f*² is provided with a plurality of buttonholes and the main part of said straps 75 below the openings *e* with a button *j*, whereby the length of the loops *f*² may be regulated, or any suitable fastening device may be employed for this purpose.

The bottom of the blouse *a* is provided with 80 a hem *k*, through which is passed a draw cord or strap *k*², and in practice the draw cord or strap *k*² is drawn tightly around the waistband of the trousers and tied or otherwise fastened, and the blouse being longer than the 85 distance between the neck of the wearer and the waistband of the trousers the bottom portion of the blouse folds downwardly, as shown at *m*, and an attractive appearance of the blouse is thus produced.

90 It will be observed that the box-plaits *c* not only conceal the straps *f*, but give additional strength to the blouse, and said straps *f* being passed over the shoulders form a strong support for the trousers and are entirely concealed when the blouse is in use.

The box-plaits *c* may be continued downwardly to the bottom of the blouse, if desired, and other changes in and modifications of the construction described may be made without 100

departing from the spirit of my invention or sacrificing its advantages.

Having fully described my invention, what I claim as new, and desire to secure by Letters 5 Patent, is—

1. A boy's blouse provided with box-plaits which are secured to the body portion of the blouse on the outer side thereof, and which are passed over the shoulders and extend 10 downwardly at the back and front a predetermined distance, the material of the blouse at the front and back and on the inner sides of said box-plaits being provided with openings at a predetermined distance above the bottom 15 of the blouse, and suspending-straps which are passed through said box-plaits over the shoulders and the ends of which extend inwardly through said openings, said straps being provided with attaching devices adapted 20 to be connected with the waistband of the trousers, and the length of the blouse being greater than the distance between the neck of the wearer and the waistband of the trousers, substantially as shown and described.
- 25 2. A boy's blouse provided with box-plaits which are secured to the body portion of the blouse on the outer side thereof, and which

are passed over the shoulders and extend downwardly at the back and front a predetermined distance, the material of the blouse at 30 the front and back and on the inner sides of said box-plaits being provided with openings at a predetermined distance above the bottom of the blouse, and suspending-straps which are passed through said box-plaits over the 35 shoulders and the ends of which extend inwardly through said openings, said straps being provided with attaching devices adapted to be connected with the waistband of the trousers, and the length of the blouse being 40 greater than the distance between the neck of the wearer and the waistband of the trousers, and the bottom of said blouse being provided with a draw-cord, substantially as shown and described.

45

In testimony that I claim the foregoing as my invention I have signed my name, in presence of the subscribing witnesses, this 31st day of August, 1904.

SAMUEL HIRSCH.
